UNITED STATES PATENT OFFICE

HENRY HAHN, OF CEDARHURST, NEW YORK

AEROPLANE

Application filed October 28, 1930. Serial No. 491,659.

This invention relates to certain improvements to aeroplanes of the so-called helicopter or giro type, although as the description proceeds it will be evident that normal flying conditions of the present day conventional lighter-than-air machine are provided for in flight. Broadly, the principal object of the invention is to provide for a change in position of certain of the propellers of an aeroplane whereby traction can be secured at an angle to the normal direction of flight. More specifically, the invention provides for the change in position of certain of the propeller shafts with respect to the horizontal and/or with respect to the longitudinal axis of the aeroplane.

A further broad object of the invention is to provide adjustable wing sections which may be so controlled as to retard the flight of an aeroplane, acting as air brakes opposing forward motion.

The two general objects set forth above may be attained in the simplest embodiment by mounting the adjustable propeller shafts directly on the adjustable wing sections so that when the wing sections are tilted the propeller shafts are tilted to the same degree. In this manner, when the propeller shafts are turned to a substantially vertical position the wing sections will be found in substantially vertical positions giving the most favorable conditions for direct vertical lift by the propellers. With the parts in such position the slip streams from the propellers will be free from direct reaction from any solid part of the aeroplane.

While it is recognized that changes in the character of motors, propellers and wings may be made the invention is not limited in principle to the application of the improvements in respect of these parts but will lend themselves to use in any suitable type of plane having any suitable engines, propellers and wings for the purpose.

The construction illustrated herein is intended to be somewhat diagrammatic and merely for the purpose of illustrating the principles involved in the invention without respect to the details of design. In the preferred embodiments, however, it will be

found that adjustable propellers are carried by motors which themselves are adjustable by suitable controlling mechanism to give the desired angular direction to the propeller shaft, thereby changing the traction forces as may be desired.

By means of the improvements certain of the propellers of an aeroplane may be so disposed as to exert a direct vertical lift for the plane, as when it is taking off or landing or hovering. In flight the propeller shafts may be moved into such line as will give maximum traction and speed. If in flight it is desired to retard the flying speed of the plane abruptly or to ease the plane down vertically when landing, the adjustable wing sections may be turned so as to present retarding surfaces checking the forward movement while at the same time the lifting force of the propellers is employed to sustain the plane to any desired extent.

Any intermediate position desired may be obtained for the propeller between one of vertical lift and one of forward flight.

Further, in accordance with the preferred embodiment certain of the propellers are adjustable angularly with respect to the direction of normal flight so as to assist in changing direction or to set up a component of force sufficient to counteract drift caused by windage. In such embodiment, in the simplest form, each propeller so adjustable is carried with a motor whose longitudinal axis is adjustable angularly within desired limits.

The invention will be described in greater detail hereinafter in connection with the embodiments shown in the accompanying drawings, wherein:

Figure 1 is a view in plan of a tri-motored plane of somewhat conventional form having adjustable wing sections on which two of the motors are mounted.

Figure 2 is a view in side elevation of the machine shown in Figure 1 indicating in dotted lines the position of the wing sections and motors when turned through approximately 90°.

Figure 3 is a longitudinal section through the plane shown in Figure 1 as seen from the front and illustrating actuating mecha-

nism whereby the propellers may be adjusted in two planes.

Figure 4 is a fragmentary view in side elevation showing hydraulic mechanism suitable for turning the adjustable wing sections on their horizontal trunnions, the view being taken on the line indicated at 4-4 in Figure 3.

Figure 5 is a fragmentary enlarged view of 10 the operating mechanism whereby the propellers may be turned angularly in a horizontal plane, the view being taken on the line 5-5 of Figure 3.

Figure 6 is a detailed view in section 15 through one of the adjustable wing sections and taken on the plane indicated by the line 6-6 of Figure 3.

Figure 7 is a fragmentary view in side elevation of a modified construction in which 20 the wing with the motor mounted thereon is revolvable about an axis extending longitudinally of the wing.

Figure 8 is a fragmentary view in front elevation of a plane such as is illustrated 25 in Figure 7 showing the wings on opposite sides of the fuselage revolvable about their own axes, the supporting mechanism being shown in section.

Figure 9 is a fragmentary view in side elevation of a further modification showing a motor and propeller mounted below the wing and movable about a transverse axis.

Figure 10 is a fragmentary view in plan 30 showing the relationship of two motors mounted like the one illustrated in Figure 9.

The aeroplane shown in Figure 1 may be of conventional construction including a fuselage *a* and side wings *b* and *c*. At the 40 forward end of the fuselage is mounted a propeller *d* while on the two wings *b*, *c*, are mounted other motors *e*, *f*, constituting a tri-motored plane. The two motors *e*, *f* are mounted on wing sections *b'*, *c'*, respectively. These two wing sections may be similar to the respective wings and in normal 45 position present no protrusion. They are mounted in their respective wings so as to revolve about transverse axes. As shown in Figure 3 the wing section *c'* is supported at one side on a trunnion *c''* and on the other side by an extended hollow shaft *c''*, anti-friction bearings being used wherever desired. Similarly, the wing section *b'* is mounted at one 50 side of a horizontal trunnion *b''* and at the other side on an extended hollow shaft *b''*. The tubular trunnions *b''*, *c''* are secured fixedly together by a cross beam *g* so that they may be rotated as a unit, being aligned axially.

60 The beam *g* carries a sector *g'* which may be engaged by a sliding rack *h* adapted to be reciprocated by power means such as hydraulic mechanism represented generally at *i*. The invention is not limited to the operating mechanism but that illustrated by way

of example will make clear the principle. As shown, it is proposed to employ a hydraulic pump *k* which is piped to the cylinder *i*, the pump being driven from any suitable source of power illustrated conventionally as an electric motor *k'* which may be under the control of the operator. A suitable valve control *l* within the reach of the operator may be used to introduce fluid from the pump to either side of the piston or can blank off both sides so that the parts may be held in any intermediate position. The trunnions *b''*, *c''*, are secured fixedly to the adjustable wing sections *b'*, *c'*, respectively. By rotating the trunnions under the influence of the power mechanism described, or otherwise, these wing sections may be tilted simultaneously from their normal positions, through 90°, to the position indicated by dotted lines in Figure 2, or to any intermediate position. When 85 the wings are thus tilted upwardly it will be apparent that the propellers of the motors *e*, *f*, will exert a direct vertical lift, the slip streams being arranged to pass without hindrance through the opening in the wings in which the sections *b'*, *c'* are mounted. It will further be observed that the effect of 90 tilting the wing sections *b'*, *c'* is to present retarding surfaces in case the plane is in normal flight so that its flying speed may be 95 quickly reduced as when hovering or landing. At such a period of time, however, the propellers are effective to exert maximum lift.

A further object of the invention is to provide for the angular adjustment of the propellers in horizontal planes so that they may be traversed as indicated in dotted lines in Figure 1. To this end, the motors *e*, *f*, are shown as mounted on the wing sections *b'*, *c'*, respectively, on anti-friction bearings *m*. The base of each motor may have a downwardly extending shaft *n* about which the motor can be turned. Each shaft may have a bevel gear *n'* fixed thereon and engaged by a bevel pinion *o*, these bevel pinions being carried on a through shaft *o'* whereby rotation of the shaft *o'* will effect simultaneous and equal angular movement of the two motors *e*, *f*. It will be noticed that the bevel gears *n'* are reversed with respect to one another so that the movements of the motors will be in the same direction when turned. To cause this turning the shaft *o'* which may extend loosely through the hollow trunnions *b''*, *c''*, 110 may have keyed thereon a crank arm *o''* connected by suitable linkage to an operating worm *p* on a shaft *p'* which can be turned by the operator. The worm *p* engages a sector *o''*, the mechanism being irreversible. From the description given it will be apparent that when the operator desires to adjust the motors angularly, as in a horizontal plane, as illustrated in Figure 1, the shaft *p'* may be turned in the desired direction thereby 115 120 125 130

rocking the shaft o' and causing simultaneous turning of the motors e, f , with their respective propellers in the desired direction and to the desired extent. Such an adjustment will change the direction of traction of the propellers so as to assist in changing direction of flight or in counteracting driftage of the aeroplane where there is a cross wind.

In the construction illustrated it will be ad-
visable to insure synchronous operation of the propellers and for that purpose their shafts may be interconnected by a cross shaft r , universal joints r' therein serving to afford capacity for angularity as between the various interconnected parts. Not only does the shafting r insure synchronous rotation of the propeller shafts but it acts as a positive drive from one shaft to the other in case either one of the motors cuts out.

In the embodiment shown in Figures 7 and 8 the fuselage is indicated conventionally at s and carries at its vertical side walls anti-friction bearings s' in which are mounted the two wings t, t' by supporting frames t^2 . These supporting frames are cross connected by a shaft t^3 making practically a unitary and revoluble structure, the wings being rotated on the axis of the shaft t^3 . Truss rods t^4 serve to brace the wings in their supporting frames. On the shaft t^3 may be secured means for effecting tilting of the wings in the manner suggested. A rack u is keyed to the shaft t^3 and may be operated by any power element such as a motor u' rotating a shaft and worm u^2 which worm engages the sector u as will be clear. In this embodiment one of the wing motors is illustrated at v , there being provided such a motor on each wing t, t' . When and as the wings are revolved about their horizontal axes their motors and propellers have their position simultaneously and correspondingly changed so that the wings may be caused to act as brakes to retard forward flight at any time and the propellers may have their shafts turned to vertical positions to give maximum lift.

In Figures 9 and 10 still another embodiment of certain of the improvements is illustrated, the adjustable motors w being shown as mounted below the wing structure T on horizontal trunnions and are capable of being turned from a horizontal position to a position in which the propeller shafts are vertically disposed, the propellers being directed downwardly. The motors may be interconnected in this case by a hollow trunnion rod, as indicated at w' in dotted lines in Figure 10 and suitable power means such as that illustrated in Figure 7 may be employed to revolve this shaft w' to tilt the motors simultaneously and to the extent desired.

As pointed out hereinbefore, the parts are illustrated somewhat diagrammatically herein since it is to be understood that the invention is not to be limited to details of the design of the parts employed, suitable motors,

propellers, wings and other structural features of the aeroplane being wholly a matter of selection for the purpose. As to each embodiment, however, there is shown a distinct principle adaptable to aeroplane practice. 70

What I claim is:

In an aeroplane, wing sections mounted revolvably on transverse axes, motors mounted on the wing sections and carrying propellers, means to revolve said wing sections and motors about said transverse axes, and shafting interconnecting the propeller shafts operatively to synchronize the propellers. 75

This specification signed this 24th day of October, A. D. 1930. 80
